Patented June 30, 1959

185,589

PUNCH PRESS FOR TERMINAL CRIMPING

Alva F. Allen, Jr., Clinton, Mo.

Application October 30, 1958, Serial No. 53,224

Term of patent 14 years

(Cl. D63—1)

Fig. 1.

Des. 185,589

PAGE 2

Fig. 2.

Fig.3.

Fig. 1 is a perspective view of the front and one side of a punch press for terminal crimping embodying my new design;

Fig. 2 is a perspective view of the rear and the side shown in Fig. 1; and

Fig. 3 is a perspective view of the rear and the side opposite to that shown in Fig. 1.

I claim:

The ornamental design for a punch press for terminal crimping, as shown.
